United States Patent Office

Des. 221,774
Patented Sept. 7, 1971

221,774

CARTRIDGE USED FOR RECORDING AND REPRODUCING

Tamao Ikuta and Shozo Moriya, Kanagawa-ken, Japan,
assignors to Canon Kabushiki Kaisha, Tokyo, Japan

Filed May 21, 1970, Ser. No. 23,085

Term of patent 14 years

Int. Cl. D14—01; D16—99
U.S. Cl. D26—14

FIG. 3

FIG. 6

FIG. 1

FIG. 5

FIG. 4

FIG. 2

FIG. 1 is a front elevational view of the cartridge used for recording and reproducing embodying our new design;

FIG. 2 is a rear elevational view of the cartridge used for recording and reproducing shown in FIG. 1;

FIG. 3 is a top plan view of the cartridge used for recording and reproducing shown in FIGS. 1 and 2;

FIG. 4 is a bottom plan view of the cartridge used for recording and reproducing shown in FIGS. 1—3;

FIG. 5 is an end elevational view of the cartridge used for recording and reproducing as viewed from the right in FIG. 1; and

FIG. 6 is an end elevational view of the cartridge used for recording and reproducing as viewed from the other end.

We claim:

The ornamental design for a cartridge used for recording and reproducing, as shown.
